DRAPERY TRAVERSE ROD

H. Henry Martens, North Haven, Conn., assignor to The Stanley Works, New Britain, Conn., a corporation of Connecticut

Filed Sept. 28, 1965, Ser. No. 87,200

Term of patent 14 years

(Cl. D21—1)

FIG. 2

FIG. 4

FIG. 3

FIG. 1 is a front perspective view of a drapery traverse rod showing my new design whereby the face plate of the end bracket is substantially planar to the surface of the rod member;

FIG. 2 is a fragmentary front perspective view of a drapery traverse rod showing an embodiment of my new design whereby the face plate of the end bracket is in stepped relationship to the surface of the rod member;

FIG. 3 is a sectional view on an enlarged scale taken on line 3-3 of FIGS. 1 and 2; and

FIG. 4 is an end elevational view of FIG. 2.

Portions of the design of FIG. 1 have been shown broken away to indicate indeterminate length and portions have been omitted from FIG. 2 for convenience of illustration.

The dominant features of the design reside in the portions shown in full lines, and a characteristic feature of the design is the provision of a linear groove on the front

face of and throughout the length of the traverse rod and extending into the end brackets with downwardly turned angular sections at each end thereof.

I claim:

The ornamental design for a drapery traverse rod, as shown and described.
